VALVE SEAT GRINDER STONE CARRIER
ASSEMBLYGeorge M. Walraven, Kenosha, Wis., assignor to
Snap-On Tools Corporation, Kenosha, Wis.

Application May 1, 1941, Serial No. 391,296

10 Claims. (Cl. 51—241)

This invention relates to valve seat grinding machines and more particularly to valve seat grinder stone carriers, although certain features thereof may be employed with equal advantage for other purposes.

It contemplates more especially the provision of a valve grinding stone carrier assembly having improved anti-friction and coating means that are conducive to better operation, longer wear and increased adaptability.

Numerous types of valve grinding stone carrier assemblies have heretofore been proposed, but these have not proven entirely satisfactory from a functional standpoint. In assemblies of this type that involve anti-friction means such as ball bearings between the outer and inner sleeve, it is usually found that the inner sleeve that serves to receive the pilot, revolves with the outer sleeve so that little or no effective purpose is served by the anti-friction means disposed therebetween. It is intended, therefore, to provide instrumentalities that prevent the inner sleeve from rotating relative to the pilot or guide.

One object of the present invention is to improve the construction and simplify the operation of devices of the character described.

Another object is to provide improved means for maintaining the inner and outer sleeves in relative rotation through the medium of anti-friction bearings.

Still another object is to provide improved means for maintaining the inner sleeve of a valve grinding stone carrier, stationary relative to the pilot or guide customarily used in conjunction therewith.

A further object is to provide improved friction engaging means between the inner sleeve and pilot of a valve grinding stone carrier assembly.

A still further object is to provide improved friction engaging means between the inner sleeve and pilot guide of a valve grinding stone carrier assembly.

Still a further object is to provide a novel combination of friction and anti-friction means in a grinder stone carrier to insure relative rotation between the inner and outer sleeves thereof.

Other objects and advantages will appear from the following description of an illustrative embodiment of the present invention.

In the drawing:

Figure 1 is a perspective view of a driver having a driving knuckle in connection with a valve driving stone carrier embodying features of the present invention.

Figure 2 is a sectional view in elevation of a valve grinding stone carrier embodying features of the present invention.

Figure 3 is a view in elevation of a grinding stone, parts thereof being shown in section to clarify the illustration.

Figure 4 is a top plan view of a valve grinding stone carrier shown in Figure 2.

Figure 5 is a sectional view taken substantially along line V—V of Figure 2.

Figure 6 is a sectional view taken substantially along line VI—VI of Figure 2.

Figure 7 is a fragmentary view in elevation of the upper portion of a pilot stem of the type adapted to be fitted in the valve stem bore preparatory to grinding a valve seat.

The structure selected for illustration is illustrated in connection with a power driver 10 that terminates in a polygonal knuckle 11 having its sides converge to a point 12 so that its largest diameter is removed or spaced therefrom. The driver knuckle 11 is adapted to be telescopically received in a correspondingly sized polygonal socket 13 broached or otherwise provided in a tubular tool holder cap 14. The tool holder cap 14 is provided proximate the lower end thereof with a cylindrical surface 15 of somewhat smaller diameter than the larger exterior portion 16 thereof in order to present a peripheral portion 17. The cylindrical surface 15 with its shoulder 17 serves to receive an elongated tubular exterior sleeve 18 that is pressed or otherwise telescoped thereover for abutment with the peripheral shoulder 17.

To this end, the inside diameter 19 of the outer sleeve 18 proximate to its upper portion corresponds with the interior diameter of the cylindrical surface 15 to provide for a tight or pressed fit therebetween. To preclude any possible separation between the tubular cap 14 and the outer sleeve 18, a plurality of stud screws 20, in this instance three (Figure 5), are disposed radially through correspondingly threaded and aligned apertures 21—22 provided in the cap 14 and outer sleeve 18, respectively, along equidistant radii.

This precludes any separation between the driving cap 14 and the outer sleeve 18 so that one will rotate responsive to the corresponding rotation of the driver knuckle 11 that is a complement of the socket 13.

As shown, the outer sleeve 18 extends downwardly to terminate in a reduced cylindrical tubular boss 23 which is exteriorly threaded as at 24 to mesh with corresponding threads 25 provided in a metallic bushing 26 comprising the

core of a grinding wheel 27. The reduced tubular boss 23 defines an exterior peripheral shoulder 28 disposed parallel to stepped interior peripheral surfaces 29—30, the latter being disposed somewhat lower than the former which merges with the inner cylindrical wall 31 of the outer sleeve 18. The cylindrical wall 31 of the outer sleeve 18 is of somewhat smaller diameter than the upper counterbore 15 thereof for snugly receiving the correspondingly sized cylindrical wall 15 of the tool holder cap 14, thereby presenting a peripheral shoulder 32 between the outer sleeve bore 31 and its counterbore 15.

A ball bearing retainer disc 33 rests on the shoulder 32 within the counterbore 15 to present an upraised axial projection 34 of comparatively smaller diameter than the inner bore 35 of the tool holder cap 14. This provides for ample space within which a coil spring 36 that envelops the upraised axial retainer disc projection 34 so as to support the disc 37 against the peripheral shoulder 38 defined by a driver cap bore 35 which terminates in communication with the somewhat smaller vertical socket 13 therein. As shown, the spring supporting disc 37 has a rounded peripheral exterior edge 39 to permit the tilting thereof as the spring 36 is caused to yield responsive to pressure exerted by the driver knuckle 11 thereon.

In order to center the driver knuckle 11 on the spring supporting disc 37, the latter is provided with an axial aperture 40 which is somewhat larger than the tip 12 of the knuckle 11 for reception therein. It should be observed that the axial boss 34 on the retainer disc 33 is inwardly recessed to provide the bore 41 for freely receiving the upper extremity 42 of a pilot stem guide 43. The pilot stem guide 43 may be of any suitable type and is intended for mounting in the valve stem bore of an internal combustion engine cylindrical head. The bore 41 is somewhat larger than an internal bore 44 provided axially through an inner sleeve 45 that is intended for reception of the pilot stem 42 therein.

In order to enable relative free rotation with minimum friction between the outer sleeve 18 and the inner sleeve 45, anti-friction means such as standard ball bearing raceways 46 and 47 are interposed between the outer sleeve 18 and the inner sleeve 45. To this end, the inner sleeve 45 is provided with a reduced annular extremity 48 defining a peripheral shoulder 49 for the reception of the upper raceway 46 thereon and support the spring retainer disc 33 in position. The lower raceway 47 is mounted on the stepped cylindrical interior surface 29 of the outer sleeve 18 for coaction with an angular seat 50 provided on the inner sleeve 45 proximate to the lower end thereof.

The angular seat 50 defines a peripheral shoulder 51 that serves to support the inner sleeve 45 on the lower raceway 47 so that the outer sleeve 18 is rotatively and vertically supported through the ball bearing raceways 46—47 through the medium of an inner sleeve 45 that establishes contact with the pilot stem 43 as will appear more fully hereinafter. The inner sleeve 45 terminates in a reduced cylindrical extension 52 that is freely received within the tubular boss 23 of the outer sleeve 18 so that the pilot stem 43 will be guided entirely through the inner sleeve 45 without contact with the outer sleeve 18 or any portion thereof.

The pilot stem 43 is usually held stationary within the valve stem bore comprising a part of

the cylindrical head of an internal combustion engine. It is desired that the inner sleeve 45 be maintained stationary with the stem 43 so that the outer sleeve 18 will be freely rotatable relative thereto through the medium of the anti-friction means such as ball bearing raceways 46—47. To insure that the inner sleeve 45 will be held stationary with the pilot stem 43, the inner sleeve 45 has an enlarged cylindrical boss 53 through which a plurality of spring impelled detents 54, in this instance three, are radially urged in communication with the external axial bore 44 of the inner sleeve 45.

The spring impelled detents 54 are, in this instance, of the ball type and are lodged in radial bores 55 provided in the enlarged peripheral boss 53 of the inner sleeve 45 along equi-spaced radii so as to project within the internal axial bore 44 of the inner sleeve 45. This is rendered possible by small apertures 56 which constitute the terminal end of the comparatively larger radial bores 55 at their point of communication with the axial inner sleeve bore 44. Springs 57 are provided in the radial bores 55 behind the ball detents 54 which urge them radially inward to project into the axial inner sleeve bore 44.

The ball detents 54 and their springs 57 are maintained assembled in the bore 55 by means of discs 58 that are pressed to tightly engage the somewhat larger counterbores 59 in axial communication with the radial bores 55. The spring impelled detents 54 will engage the pilot stem 43 and effect their relative frictional association and still permit the pilot stem 43 to be displaced axially relative to the inner sleeve 45 so that the outer sleeve assembly 18 may be telescopically displaced over and removed from the pilot stem 43 in that the detents 54 will yield to permit this engagement and disengagement.

So that the frictional engagement between the spring impelled detents 54 and the pilot stem 43 may be rendered more certain, should commercial practice so dictate, the pilot stem 43 may be provided with slight circular depressions 60 (Figure 7) that are equi-distantly spaced about a common circumference of the pilot stem 43 to render more positive the frictional engagement of the spring impelled detents 54.

In order to preclude accidental detachment between the driver knuckle 11 and the outer socket 13, the latter is provided with an annular groove 61 proximate to the upper open edge 62 thereof to receive a split wire ring 63. The split wire ring 63 is of somewhat lesser diameter than the annular groove 61 so that the inner circumferential edge thereof will lie within the exterior confines of the socket 13 with sufficient space in the annular groove 61 to permit the outward expansion of the ring 63. Consequently, the largest diameter of the driver knuckle will be somewhat greater than the normal inside diameter of the split wire ring 63 to cause the latter to expand responsive to the displacement of the driver knuckle 11 therethrough for registry with the socket 13 when the driver knuckle tip 12 is within the axial aperture 40 of the spring supported disc 37.

In this position the larger diameter of the knuckle 11 will pass beyond the split ring 63 which will then contract to its normal diameter over the driver knuckle 11 and preclude its accidental removal from the socket 13 and still permit its insertion therein without any appreciable difficulty. This arrangement affords a

simple and inexpensive spring retainer for the driver knuckle 11 when it is in its operative position of full registry with the outer sleeve holder cap socket 13.

With the arrangement of parts above described, simple and dependable expedients have been provided to maintain the driver knuckle 11 in registry with the socket 13 against accidental displacement for positive rotation of the outer sleeve 18 relative to the inner sleeve 45 which is held in position by the spring impelled detents 54 so that the anti-friction means such as the ball bearing raceways 46-47 will serve to support and rotate the outer sleeve 18 relative to the inner sleeve 45 which is in operative association with the pilot stem 43 during the valve grinding functioning of the wheel 21.

Various changes may be made in the embodiment of the invention herein described without departing from the invention or sacrificing any of the advantages or features thereof, and nothing herein shall be construed as limitations upon the invention, its structural embodiment or concept as to the whole or any part thereof except as defined in the appended claims.

I claim:

1. In a device of the character described, the combination with an outer driving sleeve, a tubular pilot receiving sleeve concentrically disposed in said driving sleeve, anti-friction means interposed between said driving and pilot receiving sleeve, and friction engaging means in said pilot receiving sleeve projecting in the path of a pilot inserted therein to retain said pilot receiving sleeve stationary relative to said outer driving sleeve.

2. In a device of the character described, the combination with an outer driven sleeve, a tubular pilot receiving sleeve concentrically disposed in said driving sleeve, anti-friction means interposed between said driving and pilot receiving sleeve, and spring impelled friction engaging means in said pilot receiving sleeve projecting radially in the path of a pilot inserted therein to retain said pilot receiving sleeve stationary relative to said outer driving sleeve.

3. In a device of the character described, the combination with an outer driving sleeve, a tubular pilot receiving sleeve concentrically disposed in said driving sleeve, anti-friction means interposed between said driving and pilot receiving sleeve, and friction engaging means comprising spring impelled detents in said pilot receiving sleeve projecting in the path of a pilot inserted therein to retain said pilot receiving sleeve stationary relative to said outer driving sleeve.

4. In a device of the character described, the combination with an outer driving sleeve, a tubular pilot receiving sleeve concentrically disposed in said driving sleeve, anti-friction means interposed between said driving and pilot receiving sleeve, and a plurality of friction engaging means comprising spring impelled ball detents in said pilot receiving sleeve projecting in the path of a pilot inserted therein to retain said pilot receiving sleeve stationary relative to said outer driving sleeve.

5. In a device of the character described, the combination with an outer driving sleeve, a tubular pilot receiving sleeve concentrically disposed

in said driving sleeve, anti-friction means interposed between said driving and pilot receiving sleeve, and a plurality of friction engaging means comprising spring impelled ball detents in said pilot receiving sleeve projecting radially in the path of a pilot inserted therein to retain said pilot receiving sleeve stationary relative to said outer driving sleeve.

6. In a device of the character described, the combination with an outer driving sleeve, said outer driving sleeve having a polygonal driver receiving socket, a tubular pilot receiving sleeve concentrically disposed in said driving sleeve, anti-friction means interposed between said driving and pilot receiving sleeve, and friction engaging means in said pilot receiving sleeve projecting in the path of a pilot inserted therein to retain said pilot receiving sleeve stationary relative to said outer driving sleeve.

7. In a device of the character described, the combination with an outer driving sleeve, said outer driving sleeve having a polygonal driver receiving socket, a tubular pilot receiving sleeve concentrically disposed in said driving sleeve, anti-friction means interposed between said driving and pilot receiving sleeve, and spring impelled friction engaging means in said pilot receiving sleeve projecting radially in the path of a pilot inserted therein to retain said pilot receiving sleeve stationary relative to said outer driving sleeve.

8. In a device of the character described, the combination with an outer driving sleeve, said outer driving sleeve having a polygonal driver receiving socket, a tubular pilot receiving sleeve concentrically disposed in said driving sleeve, anti-friction means interposed between said driving and pilot receiving sleeve, and friction engaging means comprising spring impelled detents in said pilot receiving sleeve projecting in the path of a pilot inserted therein to retain said pilot receiving sleeve stationary relative to said outer driving sleeve.

9. In a device of the character described, the combination with an outer driving sleeve, said outer driving sleeve having a polygonal driver receiving socket, a tubular pilot receiving sleeve concentrically disposed in said driving sleeve, anti-friction means interposed between said driving and pilot receiving sleeve, and a plurality of friction engaging means comprising spring impelled ball detents in said pilot receiving sleeve projecting in the path of a pilot inserted therein to retain said pilot receiving sleeve stationary relative to said outer driving sleeve.

10. In a device of the character described, the combination with an outer driving sleeve, said outer driving sleeve having a polygonal driver receiving socket, a tubular pilot receiving sleeve concentrically disposed in said driving sleeve, anti-friction means interposed between said driving and pilot receiving sleeve, and a plurality of friction engaging means comprising spring impelled ball detents in said pilot receiving sleeve projecting radially in the path of a pilot inserted therein to provide depressions confronting said friction means of said pilot receiving sleeve to render the latter stationary relative to said outer driving sleeve.

GEORGE M. WALRAVEN.
